UNITED STATES PATENT OFFICE.

MOSES C. NIXON, OF CHICAGO, ILLINOIS.

WINDMILL.

Application filed January 3, 1921. Serial No. 434,754.

To all whom it may concern:

Be it known that I, MOSES C. NIXON, of the city of Chicago, in the county of Cook and State of Illinois, have invented certain new and useful Improvements in Windmills, of which the following is a specification.

The objects of my invention are to provide for automatic lubrication of certain parts and such other improvements as may hereinafter appear; and consists, preferably, in the construction hereinafter described which may be varied without departing from the spirit of my invention.

In the drawings Figure 1 is a side elevation of a windmill head having an incasement with the nearer side of the covering cut away to better show the interior; Fig. 2 is a plan view of the same with the covering removed; Fig. 3 is a sectional view showing the upper sprocket wheel, clutches, and the hub of pivoted frame or member and receptacles in section, and connecting parts; Fig. 4 is a section of Fig. 3 on line 4, 4; Fig. 5 is a detail view of the pivoted frame; Fig. 6 is a detail view of hub of the pitman and a part of the latter; Fig. 7 is an end view of the hub shown in Fig. 6, with the rim in section to better show the receiving reservoir; Fig. 8 is an end view of hub of pump-rod head; Fig. 9 is a side view of Fig. 8; Fig. 10 is a sectional view of a section of Fig. 5 on line 10, 10; Fig. 11 is a plan view of an upward extending form within the incasement through which the pump-rod operates, with a covering to prevent oil from dripping through the opening and for excluding dust from the incasement; Fig. 12 is a sectional view of Fig. 11 on line 12, 12; Fig. 13 is a modification of the mechanism forming an operating connection between the hub of pivoted frame and the upper sprocket-wheel; Fig. 14 is another modification of mechanism which forms an operating connection between the pivoted frame and the upper sprocket-wheel, and Fig. 15 is another modification of operating connection between the pivoted member and the elevator.

Referring to the drawings, similar numerals of reference indicate corresponding

parts in the different views, in which 1 is the incasement, which in this case forms the main or supporting frame, and 2 is a covering for the same. For the purpose of furnishing automatic lubrication for certain parts, the incasement or main-frame is made to form a reservoir or container 3, for holding a supply of oil, of which 4 indicates its level.

To simplify the incasement or main-frame, supports 5 are made separately and secured thereto, as by bolts 6, and to prevent oil from escaping through these bolt holes the surface around them is raised and ribs 7 extend therefrom to furnish a better foundation for the supports. The surface around the holes in the base of the supports is also raised to prevent oil from escaping from incasement, as by bosses 8.

It being desirable to retain and return the surplus oil from the journal bearings to the reservoir, it is necessary to avoid openings through which the oil might escape, the heads of bolts are anchored in grooves 10, and to give free access to the reservoir, channels 11 beneath the bearings are provided.

Journaled in the main-frame is the wind-wheel or driving shaft 12, to which are rigidly secured gear-pinions 13. These pinions mesh with and drive gear-wheels 14, said gear-wheels, in the present case, are preferably mounted upon stud-shafts 15. These stud-shafts are provided with heads 15' to retain said gears in place, and are rigidly held by and extend from boxes or anchors 16, said boxes or anchors being provided with downward projections 17, which projections fit into cavities or depressions in the main-frame, the object being to provide means for adjusting the stud-shafts to alignment, and furnish rigid anchorage for them without perforating the walls of the incasement, thereby preventing escapement of the lubricant.

For lubricating the bearings of shaft 12, each of the gear-wheels is provided with a bucket or dipper 18 with an opening or spill-way 19, so that as the gears revolve these buckets will elevate oil from the reservoir and in passing spill it into runways

20. These run-ways convey the oil to cups 21, formed on the caps of the journal boxes, which passes through holes 22 to the journals of shaft 12. This means of lubrication 5 was covered in a former application that terminated in United States Letters Patent No. 1,246,008. To lubricate the stud-shafts on which the gear-wheels are mounted, each of the latter is provided with a bucket or 10 dipper 23 that elevates oil from the reservoir, which is then conveyed via run-ways or channels 24 formed in connection with the web or along one of the arms, as the case may be, of the gear-wheels to their hub 15 and through holes 25 to the stud-shafts thereby lubricating the same.

This construction may be varied as it is quite apparent that oil may be elevated and conveyed to the stud-shafts by other means 20 than those described.

The friction caused by the end thrust of the wind-wheel shaft consumes a great deal of power, and to reduce this friction the application of an end thrust bearing has 25 been devised, in which the regular cup 26, cone 27 and balls 28 may be used in connection with a dish or convex shaped part 29 to compensate for unevenness of resisting surface 30 to permit adjustment and a more 30 uniform pressure on the balls. In application of this end-thrust bearing, in the present case, the end of shaft 12 is reduced, which forms a shoulder 31, which end passes through the appertures in the cup and cone, 35 and if need be through the aperture 32 in the dish or convex shaped part, with the shoulder 31 resting against the bearing. This bearing is automatically lubricated in connection with the bearing of the wind- 40 wheel shaft, and it is quite apparent that its construction may be varied without departing from the general principles or application of the device.

Mounted in supports 5 is a shaft 33, which 45 may be secured in any suitable manner, and upon this shaft is pivotally mounted a frame or member 34. The hub 34' of this frame is provided with hoppers or receptacles 35, 35' which are separated by a partition 36. 50 These receptacles are connected by openings 37, 37' with chambers 38, 38', which chambers are separated by a partition 36'. The object of these partitions is to prevent too much oil running to one side of the pivoted 55 frame and to assure a more even distribution to the different bearings. Chambers 38, 38' extend along the shaft and are connected with chambers 39, 39', or if desired, chambers 38, 38' may be omitted and the 60 receptacles connected with chambers 39, 39' through openings 40, 40'. These latter chambers extend along the sides of the pivoted frame, which sides are rigidly connected at their free, or opposite end from 65 the hub, by a connection 41. Near the free

end of this pivoted frame a shaft 42 is pivotally mounted in hubs or bearings 43, 43', which shaft is rigidly secured to hub 44, of pitman 45, as by pin 46. The other end of the pitman being pivotally mounted upon 70 a wrist-pin 47 that extends across and forms an operating connection with the gear-wheels 14 and is operated thereby. As this wrist-pin and connections, during operation, becomes submerged in oil in the reservoir 75 they require no further arrangement for lubrication. Each end of the hub 44 (see Figs. 6 and 7) has an extension from its lower part with a receptacle 48, 48' therein to receive the overflow of oil from bearings 80 43, 43', and holes or channels 49, 49' from said receptacles to a partition midway of the hub and openings 50, 50' therefrom to channels 51, 51' formed on the pitman 45, through which the surplus oil is returned 85 to the reservoir. The inner hubs of bearings 43, 43' are provided with downwardly extending lips or segments 52 (see Fig. 10) that enter receptacles 48, 48' to assure that the overflow of lubricant from said bearings enters said receptacles. If a free outlet from bearings 43, 43' is desired, it may be secured, as by holes 53, 53'. The object of chambers in hub 44 is to reduce amount 90 of work in reaming to fit the shaft, and particularly in making casting to permit connecting the core of this hole with those for channels 48, 48' and openings 50, 50'. Also, near the free end of the pivoted frame, 95 a shaft 54 is pivotally mounted in hubs or bearings 55, 55', which shaft is firmly secured to the hub 56 of the pump-rod head, as by pin 57, and near each end of said hub a lip or segment 58, 58' extends downward so as to prevent surplus oil or drippings from said bearings being carried toward the pump-rod 56' and escaping 100 through the tubular mast 59. An upwardly extending tubular form 60, with an opening 61 therein, through which the pump-rod 105 may be operated is provided within the incasement. This form is preferably integral with the incasement as it is essential it be so constructed as to prevent oil from escaping therefrom and it is necessary it be in line with the mast through which the pump-rod reciprocates. To reduce the chances of oil 110 dripping through it and of dust entering the incasement the opening should be as small as the changing position of the pump-rod will permit, and to further avoid these contingencies a shutter 62 is provided (see Figs. 11 and 12), which is pivotally secured to said form, as by screws 63. This shutter should be so supported as to permit free 115 movement that it may readily respond to the changing position of the pump-rod. To reduce the wear where this shutter contacts with the pump-rod it may be re-inforced 120 at that point, as by boss 64.

It is obvious that other means than the shutter may be employed, the object being to reduce the escape of oil from or entrance of dust into the incasement, consequently, 5 other means that will obtain that result may be adopted.

The incasement is provided with an extension or enlargement 1' in which bracket 65 is secured thereto, in any suitable manner, as by bolt 66, which bolt should be placed high enough to prevent oil from escaping through the bolt hole. Supported by this bracket is a sprocket-wheel 67, upon which is mounted an endless chain or elevator 68 to which buckets or dippers are attached in any suitable manner.

In the upper end of supports 5 and above shaft 33 is rigidly mounted shaft 69, which may be secured in any suitable manner, and 10 on this latter shaft is revolvably mounted a sprocket-wheel 70, which supports and transmits motion to the elevator. Extending upward from hub 34' and within receptacle 35 is a projection 71 to which may be secured, or an integral part thereof, is a segment gear 72, and mating with this gear is a segment gear 73, which is secured to or an integral part of the hub 74, that forms a part of the clutch 75. This hub is provided 15 with a run-way or channel 76 (see Figs. 2, 3 and 4), which extends close enough to the elevator to receive a supply of oil and conveys it to opening 77 and through it to chamber 78 and opening 79 to the segment 20 gears thereby furnishing lubrication to the different parts. The other part of this clutch is formed integral with one hub of the sprocket-wheel, the two halves of this 25 clutch being held in working connection by an expansion spring 80, the latter finding lodgement against one of the supports 5. To prevent backward movement of the sprocket-wheel and elevator when the hub 30 40 is rocked rearwardly thereby releasing the clutch 75, another clutch 81 is provided with teeth set in opposite direction to those of clutch 75; and to prevent hub 82, which forms a part of clutch 81 from rotating on the shaft, it is provided with a slot 83 which 45 is adapted to slide upon a stationary pin 83'. The teeth of this clutch are held in working connection by expansion spring 80', which also finds lodgement against one of the supports 5. In operation, as the pivoted 50 frame 34 is oscillated it imparts a similar movement to the segment gears which causes the hub 74 to be rocked on its shaft and through the clutch 75 imparts an intermittent forward movement to the sprocket-wheel 55 and to the elevator as the pivoted frame is raised, and as the frame is lowered the clutch teeth releases and moves back until they are again thrown into working connection by the action of the spring. While 60 this clutch is backing up, the sprocket-wheel 65

and elevator is held in advanced position by clutch 81. To prevent chain of the elevator as it leaves the sprocket-wheel dragging on the rim of the receptacles a roller 70 75 85' is provided.

A modification of the operating connection between the pivoted frame and the hub 74 is shown in Figs. 13 and 14, in which the upward projection 71' is provided with a cam 84 in operative connection with a pin 75 or projection 85 that extends from the hub 74. This hub has a run-way or channel 80' extending from near the elevator, where it receives oil and conveys it to a point over the operating connection to lubricate the 80 same. Otherwise, the construction and operation is the same as previously described.

Another modification of the operating connection between the pivoted frame and the hub 74 is shown in Fig. 15, in which a lever 86 extends from said hub and is connected at its outer end with the pivoted frame, as by rod 87. In this construction as the pivoted frame is oscillated said lever moves in unison therewith, causing the hub 74 to be rocked and operate connecting parts 85 90 as previously described.

It is apparent that various other modifications and arrangements may be made whereby oil can be elevated from the reservoir to hub 34' or to the receptacles connected therewith. To lubricate parts with oil from the elevator the buckets or dippers are so arranged that as they pass over the upper sprocket-wheel a part of the oil is delivered at each side, that is, bucket 88 has an opening 88' in its right forward corner, bucket 89 an opening 89' in its left forward corner, and bucket 90 openings 90' at both forward corners, with a partition 91 for dividing the oil. The number of buckets may be increased or decreased as required to furnish the requisite amount of lubricant and if only one bucket is used the construction shown in bucket 90 will distribute to both sides. The oil thus delivered will lubricate the clutches, sprocket-wheel shaft, operating connections and other working parts, the surplus passing into receptacles 35, 35' and from them either through 100 openings 37, 37' and chambers 38, 38', or through openings 40, 40' to chambers 39, 39' and through the latter to shaft 54 and bearings 55, 55', over and partly around the former to shaft 42 and bearings 43, 43', lubricating the different bearings, the surplus passing from the last mentioned bearings to receptacles 48, 48' and from them through channels 49, 49' and openings 50, 50' to channels 51, 51' through which it is 105 returned to the reservoir. The distribution being done by gravity after the lubricant leaves the buckets of the elevator.

However, it is not the intention to limit the means for elevating and distributing lu- 110 115 120 125

bricant to those described as it is evident that other means may readily be employed for such purposes.

While I have herein shown and described the preferred embodiment of my invention I do not wish to be limited to the details of construction shown as it is apparent changes may readily be made without departing from the spirit of my invention, but

Having thus described my invention I claim as new and desire to secure by Letters Patent the following:—

1. In a windmill, the combination with a supporting frame, stud-shafts rigid with and extending inwardly from opposite sides of

said frame, gear-wheels revolubly mounted upon said shafts, a wrist-pin connecting said gears, a pump-rod, means adapted to form an operative connection between the

wrist-pin and the pump-rod, a receptacle for lubricant, and means adapted to convey lubricant from said receptacle to the bearings for said gear-wheels for lubricating the same.

2. In a windmill, the combination with a supporting frame, of rigid stud-shafts supported by and extending inwardly from opposite sides of said frame, gear wheels revolubly mounted upon said shafts, a container

for lubricant, and means adapted to convey lubricant from said container to the stud-shafts for lubricating the bearings of said gears.

3. In a windmill, the combination with a supporting frame constructed to embody an incasement, of stud-shafts supported by said frame, anchors adapted to rigidly secure said shafts in position and permit their adjustment to alignment with each other

without perforation of the incasement, gear wheels revolubly mounted upon said shafts, a container for lubricant, and means adapted to convey lubricant from the container to the stud-shafts for lubricating the bearings of said gears.

4. In a windmill, the combination with a supporting frame, of rigid stud-shafts supported by said frame, gear wheels revolubly mounted upon said shafts, a container for lubricant, and means carried by said gears adapted to convey lubricant from the container to said shafts for lubricating the bearings of the gears.

5. In a windmill, the combination with a supporting frame, of rigid stud-shafts supported by said frame, gear wheels revolubly mounted upon said shafts, a container for lubricant, means supported by said shafts adapted to convey lubricant from the container to the bearings of said gears for lubricating the same.

6. In a windmill, the combination with a supporting frame, of rigid stud-shafts supported by said frame, gear wheels revolubly mounted upon said shafts, a container for

lubricant, dippers carried by said gears adapted to elevate lubricant from the container, and ways carried by said gears adapted to convey lubricant from said dippers to said shafts for lubricating the bearings for said gears.

7. In a windmill, the combination with a supporting frame, of a member pivotally supported at one end and having an operating connection with a pump-rod at its other end, a container for lubricant, and means including mechanical mechanism adapted to convey lubricant from said container to the pivot of said member for lubricating the same.

8. In a windmill, the combination with a supporting frame, of a member pivotally supported at one end and having an operating connection with a pump-rod, a container for lubricant, and means including an elevator adapted to convey lubricant from said container to the pivot of said member for lubricating the same.

9. In a windmill, the combination with a supporting frame, of a member pivotally supported at one end and pivotally connected with a pump-rod at its other end, a container for lubricant, and means adapted to convey lubricant from the container to the supported end of said member and thence to the pivoted connection of the pump-rod for lubricating the same.

10. In a windmill, the combination with a supporting frame, of a member pivotally supported at one end, a pitman operatively connected with the wind wheel shaft and pivotally connected with the free end of said member, a container for lubricant, and means adapted to convey lubricant from the container to the supported end of said member and thence to the pivoted connection of the pitman with said member for lubricating the same.

11. In a windmill, the combination with a supporting frame, of a member pivotally supported at one end and pivotally connected with a pump-rod at the other, a pitman operatively connected with the wind wheel shaft and pivotally connected with said member, a container for lubricant, and means adapted to convey lubricant from said container to a plurality of said pivoted connections for lubricating the same.

12. In a windmill, the combination with a supporting frame, of a member pivotally supported at one end and pivotally connected with a pump-rod at the other, a stationary container for lubricant, and means adapted to convey lubricant from said container to the pivoted connection of the pump-rod for lubricating the same.

13. In a windmill, the combination with a supporting frame, of a member equipped with a receptacle and pivotally supported at one end, a container for lubricant, means

- for conveying lubricant from the container to said receptacle, and ways for conveying lubricant from said receptacle to the pivot of said member for lubricating the same.
- 5 14. In a windmill, the combination with a supporting frame, of a member equipped with a receptacle and pivotally supported at one end, a pump-rod pivotally connected with the free end of said member, a pitman 70 operatively connected with the operating mechanism and pivotally connected with said member, a container for lubricant, means adapted to convey lubricant from said container to the receptacle, and means
- 10 15 adapted to convey lubricant from said receptacle to the several pivoted connections for lubricating the same.
- 15 16. In a windmill, the combination with a supporting frame, of a member equipped with a receptacle and pivotally supported at one end, a container for lubricant, an elevating mechanism adapted to convey lubricant from said container to the receptacle, and ways adapted to convey lubricant 80 from said receptacle to the pivot of said member for lubricating the same.
- 20 17. In a windmill, the combination with a supporting frame, of a member equipped with a receptacle and pivotally supported at one end, a pump-rod pivotally connected with the free end of said member, and a pitman pivotally connected with an operating mechanism and also pivotally connected with said member, said member being 85 formed with lubricant passage ways connecting said receptacle and said several pivoted connections for lubricating the latter.
- 25 18. In a windmill, the combination with a supporting frame, of a pivoted member equipped with a receptacle and pivotally connected with an operating pitman and a pump-rod, a container for lubricant, means for elevating lubricant from said container to said receptacle, and means adapted to 90 convey lubricant along said member to its pivoted connections with the pitman and pump-rod for lubricating said connections.
- 30 19. In a windmill, the combination with a supporting frame, of an oscillating member pivotally connected with operating means and a pump-rod, a container for lubricant, and means adapted to convey lubricant from said container to the several 95 pivoted connections of said member with the operating means and the pump-rod for lubricating said connections.
- 35 20. In a windmill, the combination with a supporting frame, of an oscillating member pivotally supported at one end and carrying a pump-rod at the other, and means for supplying lubricant to the pivotal support of said member, said member being formed with ways arranged to convey lubricant 100 from its pivotally supported end to the pump-rod connection whereby said connection may be lubricated.
- 40 21. In a windmill, the combination with a supporting frame, of a power transmitting mechanism including a pitman, a member pivotally supported at one end and operatively attached to said pitman, at the other end, a container for lubricant, and means for conveying lubricant from said container to the pivoted connection between the pitman and said member for lubricating the same, said pitman being formed with ways arranged to drain lubricant 105 from said connection to the container.
- 45 22. In a windmill having an oscillating member pivotally supported at one end and pivotally connected with a pump-rod at the other, means for supplying lubricant to the pivot of the pump-rod for lubricating the same, and means for preventing the drainage of lubricant from said pivot toward the pump-rod.
- 50 23. In a windmill, the combination with a supporting frame, of an incasement, power transmitting and lubricating mechanism, a tubular mast upon which said frame is mounted, a pump-rod, and a covering for the tubular mast arranged to permit the pump-rod to be operated through 110 said mast.
- 55 24. In a windmill, the combination with a supporting frame, of an incasement, power transmitting and lubricating mechanism, a pump-rod, an opening into said incasement through which the pump-rod may be operated, and a covering for said opening arranged to permit the operation of the pump-rod.
- 60 25. In a windmill, the combination with a supporting frame, of an incasement, power transmitting and lubricating mechanism, a pump-rod, an opening into said incasement, and a laterally slidible covering for said opening orificed to receive said pump-rod and arranged to accommodate the lateral 115 swing of such rod.
- 65 26. In a windmill, the combination with a supporting frame, of an incasement, power transmitting and lubricating mechanism, an opening into said incasement, a pump-rod adapted to be reciprocated through said opening, a shutter pivotally secured and arranged to form a covering for said opening, said shutter being adapted to permit the pump-rod to be reciprocated through said opening.
- 70 27. In a windmill having a power transmitting mechanism including a wind-wheel 120

6
shaft, a rolling contact thrust bearing at the end thereof, ways leading to said shaft and the thrust bearing for supplying lubricant thereto, a container for the lubricant, 5 and means for delivering lubricant from said container to said ways, thence to said shaft and thrust bearing.

28. In a windmill having a power transmitting mechanism including a wind-wheel 10 shaft, a rolling contact thrust bearing associated with said shaft, ways leading to said shaft and the thrust bearing for supplying lubricant thereto, a container for the lubricant, and moving means for delivering 15 lubricant from said container to said ways, thence to said shaft and thrust bearing.

29. In a windmill, the combination with a supporting frame, of an incasement adapted to contain lubricant, a member supported 20 at one end and pivotally connected with a pump-rod at the other, and means adapted to convey lubricant from the container to said pivoted connection for lubricating the same.

25 30. In a windmill, the combination with a supporting frame, of an incasement, power transmitting and lubricating mechanism, a pump-rod, an opening into said incasement, and means adapted to close said opening and permit the pump-rod to be operated 30 through the same.

31. In a windmill, the combination with a supporting frame, of an incasement, a container for lubricant, a member pivotally 35 supported at one end and having an operat-

ing connection with a pump-rod, power transmitting mechanism including a pitman connected with said member, and means adapted to convey lubricant from the container to said connections for lubricating 40 the same.

32. In a windmill, the combination with a supporting frame, of an incasement, a container for lubricant, a member pivotally 45 supported at one end and having an operating connection with a pump-rod, power transmitting mechanism including a pitman connected with said member, means adapted to convey lubricant from the container to said connections for lubricating the same, 50 and means adapted to return the surplus lubricant to the container.

33. In a windmill having a power transmitting mechanism including a wind-wheel 55 shaft, a rolling contact bearing associated with said shaft, ways leading to said shaft and the thrust bearing for supplying lubricant thereto, a container for the lubricant, and means to elevate lubricant from said container to said ways, thence to said shaft 60 and thrust bearing.

34. In a windmill, the combination with a supporting frame constructed to embody an incasement adapted to contain lubricant, power transmitting and lubricant feeding 65 mechanism housed in the incasement, an end thrust bearing for the wind-wheel shaft, and means whereby said bearing may be automatically lubricated.

MOSES C. NIXON.
